W. P. ALLEN

RAILWAY TRAFFIC CONTROLLING APPARATUS

Filed Aug. 4, 1926

UNITED STATES PATENT OFFICE.

WALTER P. ALLEN, OF JERSEY CITY, NEW JERSEY, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed August 4, 1926. Serial No. 126,997.

My invention relates to railway traffic controlling apparatus, and particularly to apparatus of the type comprising governing mechanism on a car controlled by current supplied to the track rails.

I will describe one form of apparatus embodying my invention, and will then point out the novel features thereof in claims.

The accompanying drawing is a diagrammatic view showing one form of apparatus embodying my invention.

Referring to the drawing, the reference characters 1 and 1^a, designate the track rails of a railway along which traffic normally moves in the direction indicated by the arrow. These rails are divided by insulated joints 2 into a plurality of track sections C—D, D—E, etc. Located at the entrance end of each section is a signal designated by the reference character S, with an exponent corresponding to the location, each of which signals is capable of indicating proceed, caution or stop. These signals may be controlled in any suitable manner, and since the apparatus for controlling them has nothing to do with my present invention, such apparatus is omitted from the drawing in order to simplify the disclosure.

Each section is provided with means for supplying the rails of the section with alternating current of one characteristic or another according to traffic conditions in advance of the section. As here shown, current of one frequency is supplied to the rails under one traffic condition, and current of a different frequency is supplied to the rails under a different traffic condition. In order to supply these currents, each section is provided with a transformer located adjacent the exit end of the section and designated by the reference character T with an exponent corresponding to the location. A secondary 6 of each of these transformers is connected across the rails of the section through a resistance 4 and a resistance 5. The primary 7 of each transformer T is connected with a transmission line L when the signal S for the next section indicates proceed or caution, and with a transmission line L^H when the signal for the next section in advance indicates stop. The connection of primary 7 to one or the other of the transmission lines is accomplished by circuit controllers 8 and 9 operatively connected with the signal for

the section next in advance. The transmission line L is constantly supplied with alternating current of a relatively low frequency by a generator M, and the transmission line L^H is constantly supplied with alternating current of a relatively high frequency by a generator M^H.

Interposed between the secondary 6 of each transformer T and one of the track rails, is a battery 3. These batteries may be used to energize the usual track relays which are employed to control the signals S, but which are not shown in the drawing because they form no part of my invention.

The reference character V designates a car traveling on the track rails 1 and 1^a. Located in advance of the forward axle of this car are two magnetizable cores 10 and 10^a, mounted above the track rails 1 and 1^a, respectively, and carrying coils 11 and 11^a, respectively, so that these coils are in inductive relation with the two track rails. The coils 11 and 11^a are included in receiving circuit H which may also include a condenser 12 or a condenser 13. These condensers are of different capacities, and are so chosen that when the condenser 12 is included in the receiving circuit this circuit is substantially tuned to resonance at the frequency of the current supplied by generator M, whereas when the condenser 13 is included in the circuit, the circuit is substantially tuned to resonance at the frequency of the current supplied by generator M^H. One condenser or the other is included in the receiving circuit according as contact 19 is in one position or the other, and this contact is connected with a manually operable member F. An amplifier 14 is connected across condenser 12 or condenser 13, according to which one of these condensers is included in the receiving circuit, and this amplifier supplies alternating current to a rectifier 15, which in turn furnishes uni-directional current to a relay 16. The parts are so adjusted that when the receiving circuit H is tuned substantially to resonance at the frequency of the particular current which happens to be flowing in the track rails, the relay 16 will be energized to close its front contacts, but that when the receiving circuit is tuned to resonance at the frequency of the other current, this relay will be de-energized.

The relay 16 may control train governing mechanism of any suitable character. As here shown, this mechanism comprises a brake application valve W, which is effective when de-energized to apply the brakes automatically. The valve W is provided with a circuit which passes from terminal B of a suitable source of current through front contact 18 of relay 16 and valve W to terminal O of the same source of current.

The car is also provided with a cab signal J, comprising three electric lamps G, Y and R, arranged to indicate proceed, caution and stop, respectively. These lamps are controlled by contact 17 of relay 16, and also by a circuit controller 20 operatively connected with the manually operable member F. When relay 16 is energized and member F is in its normal position, the proceed lamp G will be lighted by virtue of a circuit which is obvious from the drawing. When relay 16 is energized and member F is reversed, the caution lamp Y will be lighted. When relay 16 is de-energized, the stop lamp R will be lighted, regardless of the position of contact 20.

As shown in the drawing, the section immediately to the right of point E is occupied by a car V^a, so that signal S^e indicates stop, and, consequently, current of high frequency is supplied to the rails of section D—E. Signal S^c indicates caution, so that current of low frequency is supplied to the rails of section C—D. Signal S^p indicates proceed, so that current of low frequency is supplied to the rails of the section to the left of point C. The car V therefore receiving current of low frequency, and with the member F in the normal position, in which it is shown in the drawing, condenser 12 is included in the receiving circuit H, so that this circuit is tuned to resonance at the low frequency. Relay 16 is therefore energized, so that the proceed lamp G is lighted and the brake application valve W is energized. As the car passes through section C—D, no change occurs in the car-carried apparatus, because the rails of this section are supplied with current of low frequency. As the car enters section D—E, however, it will receive current of high frequency from the rails of this section, and, consequently, relay 16 will open unless the engineman reverses the manually operable member F, thereby including condenser 13 in the receiving circuit H. If the engineman fails to reverse the member F, the opening of relay 16 will de-energize the brake application valve W and so will cause an automatic application of the brakes, and the opening of relay 16 will also cause the stop lamp R to become lighted. On the other hand, if the engineman reverses the member F, relay 16 will remain energized, so that brake application valve W will continue to be energized,

but the caution lamp Y will become lighted. When the car V enters the occupied section to the right of point E, the supply of energy from the track rails will cease, and, consequently, the car will be brought to a stop unless means are provided to permit the car to proceed at a safe low speed when relay 16 is opened. Such means are well known in the train control art and need not be illustrated, because they form no part of my invention. When the car again enters a section supplied with current of low frequency, the engineman will restore member F to its normal position, whereupon relay 16 will be energized because the receiving circuit H will then be tuned to resonance at the frequency of such current.

It will be seen from the foregoing that upon passing a wayside signal indicating caution, the engineman must reverse the manually operable member F in order to avoid an automatic application of the brakes. This action indicates that the engineman is alive and alert.

Although I have herein shown and described only one form of apparatus embodying my invention, it is understood that various changes and modifications may be made therein within the scope of the appended claims without departing from the spirit and scope of my invention.

Having thus described my invention what I claim is:

1. In combination with the rails of a railway track and a car travelling thereon, means for supplying said rails with alternating current of one frequency or another according to traffic conditions in advance, a circuit on the car receiving energy from the track rails and including manually operable means for tuning the circuit to substantial resonance at the frequency of either of said currents, and governing mechanism on the car effective to retard the car if said circuit is not tuned to substantial resonance at the frequency of the current in the rails at the point occupied by the car.

2. In combination, a stretch of railway track divided into sections and a car travelling thereon, means for each section for supplying the rails with alternating current of one frequency or another according as the section next in advance is occupied or unoccupied, a circuit on the car receiving energy from the track rails and including manually operable means for tuning the circuit to substantial resonance at the frequency of either of said currents, and governing mechanism on the car effective to retard the car if said circuit is not tuned to substantial resonance at the frequency of the current in the rails of the section occupied by the car.

3. In combination with the rails of a railway track and a car travelling thereon,

means for supplying said rails with alternating current of one frequency or another according to traffic conditions in advance, a coil mounted on the car in inductive relation to a track rail, a circuit for said coil provided with two condensers of different capacities adapted respectively to tune the circuit to substantial resonance at the frequency of one or the other of said currents, 5 manually operable means for including one or the other of said condensers in said circuit, and governing mechanism on the car controlled by the voltage across whichever of said condensers is included in said circuit and effective to retard the car if said circuit is not tuned to substantial resonance at the frequency of the current in the rails at the point occupied by the car.

4. In combination with the rails of a railway track and a car travelling thereon, 20 means for supplying said rails with current of one characteristic or another according to traffic conditions in advance, governing mechanism on the car controlled by

said track rail currents, and manually operable means on the car for causing said mechanism to be effectively responsive to current of one characteristic or the other according as said manually operable means is in one position or another. 25

5. In combination with the rails of a railway track and a car travelling thereon, means for supplying said rails with current of one characteristic or another according to traffic conditions in advance, a circuit on the car receiving energy from the track rails and including manually operable means for causing the circuit to be effectively responsive to current of one characteristic or the other according as said 30 manually operable means is in one position or another, and governing mechanism on the car controlled by said circuit and operating to retard the car unless the circuit is effectively responsive to the current in the rails 35 at the point occupied by the car. 40

In testimony whereof I affix my signature.
WALTER P. ALLEN.
